CLAIM

The ornamental design for a telecontrol panel for household circuitry, as shown.

DESCRIPTION

FIG. 1 is a perspective view of a telecontrol panel for household circuitry, showing my new design;

FIG. 2 is a front elevational view thereof;

FIG. 3 is a rear elevational view thereof;

FIG. 4 is a side elevational view thereof from the left of FIG. 2;

FIG. 5 is a side elevational view thereof from the right of FIG. 2;

FIG. 6 is a top plan view thereof; and,

FIG. 7 is a bottom plan view thereof.

FIG. 1

FIG. 2

FIG. 3

FIG. 4

FIG. 5

FIG. 6

FIG. 7
